UNITED STATES PATENT OFFICE

103,544

DESIGN FOR AN AUTOMOBILE GRILLE GUARD

Anthony V. Weasler and William J. Dooley, West Bend, Wis., assignors to Pick Manufacturing Company, West Bend, Wis., a corporation of Wisconsin

Application December 4, 1936, Serial No. 66,315

Term of patent 7 years

To all whom it may concern:

Be it known that we, Anthony V. Weasler and William J. Dooley, both citizens of the United States, residing at West Bend, in the county of Washington and State of Wisconsin, have invented a new, original, and ornamental Design for an Automobile Grille Guard, of which the following is a specification, reference being had to the accompanying drawing, forming a part thereof, in which the figure is a perspective view exhibiting our new design.

We claim:

The ornamental design for an automobile grille guard, as shown.

ANTHONY V. WEASLER,
WM. J. DOOLEY,
